UNITED STATES PATENT OFFICE.

JOSEPH P. BULLOCK, OF MILWAUKEE, WISCONSIN, ASSIGNOR OF TWO-THIRDS TO THE DENNETT HARVESTING MACHINE COMPANY, (LIMITED,) OF SAME PLACE.

NEEDLE FOR GRAIN-BINDERS.

SPECIFICATION forming part of Letters Patent No. 309,026, dated December 9, 1884.

Application filed September 21, 1883. (No model.)

To all whom it may concern:

Be it known that I, JOSEPH P. BULLOCK, of Milwaukee, in the county of Milwaukee, and in the State of Wisconsin, have invented certain new and useful Improvements in Needles for Grain-Binders; and I do hereby declare that the following is a full, clear, and exact description thereof.

My invention relates to improvements in needles for grain-binders, and will be fully described hereinafter.

In the drawings, Figure 1 is a vertical section of the binder-table, showing a side view of my improved needle; and Fig. 2 shows on a larger scale said improved needle in a different position.

A is the needle or binder arm, attached in the usual way in the binder-frame B. Instead of having the tail-guard C made rigid with the needle or binder arm, as is generally done, said tail-guard is a separate part hinged on the ear *a* of the tail *a'* on the needle or binder arm, the square end of which is slightly narrowed in the form of a lug, *b*, against which said tail-guard C may rest on its shoulder *c* when the needle A occupies over the frame B the position indicated by the dotted lines, Fig. 1. This hinging of the tail-guard of the needle prevents its end from striking the ground or anything projecting from it when said needle is lowered under the frame B, as said tail-guard C is then forced to engage and slide upon the inner face of the curved deflecting-plate D, bolted in a proper place underneath said

frame B. When said needle A is raised up again, said tail-guard C is made to resume its normal position by the action of the flat spring *d*, which is fastened at one end on the inside edge of the needle-tail *a'*, and has its free end pressing against the inside edge of said tail-guard C.

Having thus described my invention, what I claim as new, and desire to secure by Letters Patent, is—

1. A needle or binder arm for a self-binding harvester, having a guard pivoted to the tail thereof, and provided with a spring for keeping the guard extended, in combination with a deflecting-plate attached to the binder-frame, adapted to be struck by and fold the guard up against the plate when the needle is lowered, substantially as and for the purpose set forth.

2. A needle or binder arm for self-binders, having the guard C hinged to the tail of the needle or binder arm on the ear *a*, the lug *b*, and the spring *d*, in combination with the curved guide or deflecting plate D, substantially as shown and described, and for the purpose set forth.

In testimony that I claim the foregoing I have hereunto set my hand at Milwaukee, in the county of Milwaukee and State of Wisconsin, in the presence of two witnesses.

JOSEPH P. BULLOCK.
